LATHE CHUCK RACK

Earl W. Saul, 1 Silver Ave., Glassboro, N.J.
Filed Sept. 24, 1958, Ser. No. 763,067
2 Claims. (Cl. 211—150)

This invention relates to supporting apparatus and, more specifically, relates to a rack for supporting and storing lathe chucks and lathe accessories when not in use.

It is therefore an object of this invention to provide a simple, compact and useful apparatus for supporting and storing lathe chucks and accessories while they are not in use.

It is another object of this invention to provide a rack with a plurality of shelves, pivotally mounted on a vertical shaft that are capable of swinging outwardly so that lathe chucks placed thereon may be made readily available to the lathe operator.

It is another object of this invention to provide a lathe accessory rack including a plurality of shelves pivotally mounted on a vertical shaft, which will support and maintain readily available practically all of the tools needed in operation of a lathe.

It is another object of the invention to provide a lathe chuck rack having a revolving tool holder.

A better understanding of the invention will be obtained from the accompanying drawings wherein:

FIGURE 1 is a view in side elevation of the rack of this invention;

FIGURE 2 is a plan view of FIGURE 1 showing the rotary tool holder;

FIGURE 3 is a view in section made along line 3—3 of FIGURE 1;

FIGURE 4 is an enlarged fragmentary view partly in section of a portion of FIGURE 1 showing two of the pivotal shelves; and

FIGURE 5 is a fragmentary side view of FIGURE 1 taken along line 5—5 of FIGURE 1.

Referring more specifically to the drawings, there is shown a rack comprising three upright supporting members 11, 11 and 11' which extend vertically from a flat base member 31 to a top member 17 which is similar in construction to base member 31. Also extending from base member 31 to top member 17 is a shaft 14 of stepped diminishing diameters, the steps of which provide shoulders 20 which assist in supporting pivotal shelves 16. It should be noted that each shelf 16 and each portion of shaft housing 32 may be joined as an integral unit. The integral unit pivots on the step 20 of the shaft 14 immediately below the integral unit. The members 11, 11 and 11' are preferably made of relatively heavy pipe and are welded to base 31 and are received by sockets 33 mounted on the underside of top plate 17. Suitable bolts 34 extend through sockets 33 and members 11, 11 and 11' to maintain said members in a fixed position.

Shaft 14 is a shaft of stepped diminishing diameters. As previously stated, the diminishing diameters of shaft 14 provide shoulders 20 on which shelves 16 may pivot. Thus, when a shelf 16 is pulled outwardly, the integral assembly consisting of shelf 16 and housing 32 rotates as a unit.

A guide ring 19 is fixedly mounted on the upper surface of each shelf 16, and hold each chuck in place on shelf 16. FIGURE 1 shows various chucks 23, 24, 25, 26, 27, and face plate 28 stored on a shelf 16. Angularly mounted around and near the base of shaft 14 is a foot 18 as shown in FIGURE 5. This angular foot

2

provides a convenient support for "steady rest" 29, which is adapted to pivot outwardly the same as shelves 16.

By viewing FIGURE 3, there can be seen two supporting members 11 and another supporting member 11' which also serves as a stop means for the larger shelves 16 which appear in FIGURE 1 as the lower two shelves. Welded to member 11' is a plate 35 which serves as a stop means for smaller shelves 16, which appear in FIGURE 1 as the top four shelves. It can be seen that when a lathe operator pushes a shelf 16 back into place, there must be a means to keep shelves 16 in static balance so that they will not be pushed back too far. Therefore, with the use of member 11' and plate 35, the lathe operator can merely push shelves 16 into place into contact with the member 11' or plate 35. The rear portion of the entire rack is enclosed by a suitable cover 36 which is attached to and extends from one member 11 outwardly around member 11' and terminates at the other member 11.

Rotatably mounted on a center axis on the upper surface of top plate 17 is a tool holder drum 15. Drum 15 has on its outer periphery slots 21 that extend inwardly and receive various lathe tools. The upper surface of drum 15 is provided with an array of holes 30 to receive such lathe accessories as live centers, dead centers, drill chucks, and spindle nose taper adaptors. Fixedly mounted on the upper surface of drum 15 are two elongated, three-sided structures forming channels 22 which are adaptable to receive a cutting off tool and a knurling tool.

The preceding description sets forth a complete, useful and efficient lathe chuck and tool rack which may be used with ease in a minimum of space, including among its principal features pivoting shelves and revolving drum tool holder which enables a lathe operator to have maximum access to his tools and accessories with minimum effort. It should also be noted that this invention will have various uses and applications for similar machine tool parts storage and the like and is not intended to be limited to a rack and tool holder for lathe accessories only.

This invention may be embodied in other specific forms without departing from the spirit or essential characteristics thereof. The present embodiment of this invention as hereinbefore set forth is therefore to be considered in all respects as illustrative and not restrictive, the scope of this invention being indicated by the appended claims, and all changes which come within the meaning and range of equivalency of the claims are therefore intended to be embraced therein.

What is claimed is:

1. A storage device comprising a frame comprising a top plate and a bottom plate, a plurality of upright members extending between and secured to said plates whereby said top plate is fixed coaxially above said bottom plate, an upright shaft of stepped diminishing diameters disposed between said plates and located eccentrically with respect to the common axis thereof, a plurality of spaced shelves having article mounting means thereon, separate housings for each step of said shaft extending over the entire space between said steps, said shelves and said housings being united to form separate integral shelf and housing assemblies, each said integral shelf and housing assemblies being supported by and pivotally mounted for movement about one step of said shaft.

2. The device of claim 1 wherein at least some of said shelves are of varying size, and including stop members mounted on one of said upright members, said stop members being adapted to align said varying size shelves

along the common axis of said plates when in stored position.
